METHOD OF SOLVENT REFINING

David F. Renshaw, Olean, N. Y., assignor to
 Socony-Vacuum Oil Company, Incorporated,
 New York, N. Y., a corporation of New York

Application December 18, 1936, Serial No. 116,508

2 Claims. (Cl. 196—13)

This invention is directed to single solvent methods for the refining of petroleum oils. These methods of refining are those wherein a petroleum oil fraction, comprising constituent groups having differing chemical properties, is subjected to admixture, in liquid form, with a solvent liquid having preferential solvent powers for one of the groups of constituents of the oil, followed by phase separation and removal of the solvent containing the extracted constituent group. The solvents as applied may or may not be mixtures of reagents, and the desirable fraction of the oil, to be obtained from the operation, may be either the portion insoluble in the solvent or the portion soluble in the solvent. In commercial adaptations of this type of refining, the solvent used is a reagent of the type of beta-beta-dichloro-diethyl ether, known as "Chlorex", phenol, cresols, nitrobenzene, furfural, aniline, and numerous other organic compounds, many of which are alcohols, aldehydes, and ethers, which, used alone, or in company with some other member of the group, has a preferential solvent power for the less desirable naphthenic constituents of the oil, is heavier than the desirable oil and settles therefrom in phase separation, and which removes the undesired oil constituent as an extract. This invention has specifically to do with operations of this type, and by way of example discusses an operation wherein the solvent used is Chlorex.

To more clearly understand this invention, reference is made to the drawing attached to this specification. In this drawing, the single figure shows a somewhat diagrammatic setup of an apparatus for the treatment of oil with Chlorex or similar solvent refining agent.

The treating system setup shown in the drawing consists of four settlers or separating drums, 1, 2, 3, 4, each preceded by and connected to a mixer, designated by 5, 6, 7, 8. Oil to be treated enters through pipe 9, passes through cooler 10, pipe 11, through mixer 5, and into settler 1. Before its entry to the mixer, it has been joined by a flow of extract from pipe 12. Oil and extract settle apart in 1 and oil flows through pipe 13, pump 14, mixer 6, into settler 2, and similarly through the subsequent pipes, pumps, mixers and settlers 15, 16, 7, 3, 17, 18, 8, 4, to emerge in pipe 19 from the top of settler 4 as raffinate or refined oil to be removed from the system. Solvent enters through pipe 20, passes through pump 18, mixer 8, and settler 4, picking up in its travel therein in company with the oil, some of the compounds to be removed, and becoming in the ter-

minology of the art, "extract". "Extract" settled in 4 flows therefrom through pipe 21 to move through pump 16, mixer 7, settler 3, pick up more tar in that stage, emerge from 3 and flow through 22, 14, 6, 2, and then, in accordance with the method in use prior to this invention, flows through 23, pump 24, pipe 12, mixer 5, and into 1. Settled tar and solvent, termed "extract" inclusively, separated in settler 1, is removed through line 25 to storage. Flow through lines 21, 22, 23, and 25 are controlled respectively by float controls 26, 27, 28, 29 working on the interface between "extract" and raffinate in the respective settlers. It will be seen that in this operation, the supply of solvent for use in any one stage is dependent, not upon the need for solvent in that stage, but upon the ability of preceding stage to reject "extract." This is particularly acute in the first stage of oil treatment, where the solvent available for flow with the incoming raw oil through mixer 5 and settler 1 is dependent not upon the proportion of solvent which should be applied to the oil, but upon conditions existing in settler 2. If the proper amount of solvent is not applied in 5, raffinate going into 6 will furnish more or less tar than optimum to settle in 2, and operation in 5 and 1 will be further deranged. It would seem that these variations should iron out in practice, but they do not and in fact such a system is subject to a continuous series of progressive disturbances and conditions of unbalanced operation working their way through the system. The net result of these is a decrease in throughput of finished oil, accompanied by a serious loss of good oil to "extract", which must be recovered and retreated, thus further cutting down the capacity of the operation. This invention is based in part upon my discovery that these difficulties can be avoided to a great degree by the provision of a method whereby the supply of reagent for use with raw oil can be adjusted with regard to the needs of the oil across any range desired without deranging subsequent portions of the operation. To do this, I install by-pass line 30, and therein a control valve operated by liquid level control 28 in settler 2, but arranged in reverse, that is, to open when the level in 2 is decreasing instead of closing, as is normal. By this means, when insufficient "extract" is collecting in 2, instead of closing pipe 23 entirely, thus depriving raw oil of any treatment, changing the nature of extract in 1 quickly, and losing good oil in extract from 1 before correction of the system, the valve in pipe 30 opens, to admit "extract" from 1 or from the 55

storage tank floating on pipe 25 and the proper conditions are maintained in mixer 5 and settler 1. Thus no change in character of raffinate occurs in units 6 and 2, and the system is given a chance to iron itself out or adjust itself to new conditions.

Rates are not the only thing in which the operation on raw oil is dependent upon the rest of the system. The temperature of the incoming oil can be controlled in the prior setup, but the temperature of the extract from 2 is dependent upon conditions of operation in 2, 3, 4, and this temperature is not always the best for conditions which should obtain in 1. The other portion of my invention is based upon the discovery that operation on raw oil could be greatly improved by controlling the temperature of the oil-extract mixture entering mixer 5 rather than by controlling only the temperature of the oil. To do this, I install a valve in pipe 12, and valved pipe 31, whereby the valve in 12 being closed, the "extract" flowing to mixer 5 is passed through cooler 10 in company with raw oil from pipe 9 and an accurate control upon temperature in mixer 5 is thus obtained.

While the description above is directed to a setup having four settling stages, it is to be understood that the details of operation herein disclosed center around the two mixing and settling stages which are first in the order of oil flow and that the invention is applicable to any system of treatment making use of two or more stages of treatment, each stage consisting of a mixing step followed by a settling step. Mixers of any convenient form may be used, and settlers may, of course, be vertical, inclined, or horizontal.

To show the effect of these changes, the following data is presented. Before changing, when treating Pennsylvania cylinder stocks with 2.2 parts Chlorex to 1 oil, nearly 10% of treating time was lost in stoppage to overcome difficulties, about 28% of the charge escaped into "extract", requiring subsequent recovery, and only about 70% yield was obtained on charge due to lost time and required rerunning. Upon the addition of the step of recirculating "extract" from

#1 settler to charge, the down time decreased to about 1%, although the charge lost to "extract" was still high due to lack of proper temperature control, and the recovery of treated oil on oil charged in a given period was raised to about 80%. Upon addition of temperature control to mixed feed to mixer 5, stoppages due to unbalanced operation were entirely eliminated, loss of charge to "extract" became negligible and the yield of treated oil on oil charged during a given period raised to about 90%, the same as the net yield, because of lack of necessity for rerunning.

I have found that when treating an oil of about 100 viscosity index, to raise it to about 107-110 viscosity index, that optimum operating conditions are obtained with a solvent oil ratio of about 2:1, a temperature on incoming solvent of about 65° F., and a temperature on feed to first mixer of about 65° F.

I claim:

1. A process of treating oil with a solvent reagent to selectively dissolve and remove therefrom naphthenic constituents comprising the following steps: flowing oil and solvent in counter current through a system comprising a plurality of stages each consisting of a contacting step and a settling step, removing from each settling stage an "extract" consisting of naphthenic constituents dissolved in a substantial amount of solvent, which "extract" is introduced into the stage next preceding in the direction of oil flow, removing an "extract" consisting of naphthenic constituents dissolved in a substantial amount of solvent from the stage in which oil is first introduced, admixing at least a portion of said "extract" last named with the "extract" withdrawn from the next succeeding stage in the direction of oil flow, and thereby initially contacting the oil to be treated with solvent at a solvent/oil ratio controllably increased over the ratio at which solvent and oil are fed to the system.

2. The method of claim 1 in which the mixture of "extracts" is admixed with oil to be treated and the resulting fluid is subjected to controlled cooling prior to entry to the treating system.

DAVID F. RENSHAW.
